UNITED STATES PATENT OFFICE.

CHARLES FRANCIS JENKINS, OF WASHINGTON, DISTRICT OF COLUMBIA.

ELECTRICAL CONTACT DEVICE.

942,647.

Specification of Letters Patent. Patented Dec. 7, 1909.

Application filed August 21, 1908. Serial No. 449,683.

To all whom it may concern:

Be it known that I, CHARLES FRANCIS JENKINS, citizen of the United States, residing at Washington, in the District of Columbia, have invented certain new and useful Improvements in Electrical Contact Devices, of which the following is a specification, reference being had therein to the accompanying drawing.

10 This invention relates to electrical contact devices for instantaneously making and again breaking circuits and it is shown for illustration as embodied in apparatus for use in connection with the igniters of a four cylinder internal combustion engine. In devices of the same class, it is common to rotate a contact piece slowly over fixed contact pieces successively, to actuate the several igniters at proper intervals. Such devices 15 maintain closed circuits during a large fraction of the entire time that the engine is in operation, making it necessary to replace the battery cells frequently, which often leads to much vexation.

20 25 The object of this invention is to eliminate these evils without introducing others. This end is attained by delaying the advance of the moving contact piece during the time that it is between successive fixed contacts 30 and then allowing a spring to throw it suddenly over the surface of the fixed contact piece.

In the accompanying drawings, Figure 1 is a perspective view of the apparatus with 35 the cover of its casing removed. Fig. 2 is an axial section of the devices shown in Fig. 1, the cover being in place.

In these views, A represents a cup-shaped casing provided with a cover A' and having 40 in its bottom a central opening for a rotary shaft B electrically connected with a battery or the like and rotated in the usual way, all as in well known devices of the same general class. Within this case and 45 equally spaced around its marginal portion are four fixed spring contact pieces C, insulated from the case and shaft and each provided with a conductor C' leading to the corresponding igniter, not shown. Within 50 the case, also, a plate D is fixed to the shaft, and upon this is centrally pivoted a conducting bar E the outer end of which serves as a moving contact piece normally in position to sweep under the fixed contacts successively as the shaft rotates. The bar is 55 held in radial position by a helical spring

E' attached to its inner end, normally alining with it, and having its own opposite end secured to the plate D. Between successive fixed contact pieces and near the outer wall of the casing is secured a mass of rigid insulating material having internal faces F forwardly and inwardly inclined in the normal path of the outer end of the pivoted bar, the inner end of each face terminating, near the corresponding fixed contact piece, at an abrupt offset in the insulating material.

In operation, the fixed and the moving contact pieces are connected with the terminals, respectively, of a battery which includes the igniters in circuit, and the shaft is slowly rotated, all in the usual way. As the shaft rotates, the contact piece E moves with it until the outer end of the bar strikes one of the inclined surfaces which cause the bar to swing upon its pivot, as shown in Fig. 1, the spring extending to permit such movement. When the rearwardly swung outer end of the bar passes from the inclined surface, the recoil of the spring throws the bar instantly to normal position upon the opposite side of the fixed contact piece, and during this instant, contact is made and again broken precisely as it would have been made and broken if the moving contact had been fixed to the shaft, except that the contact is of hardly appreciable duration. The contact is thus made with all the certainty of the slow contact but the battery energy consumed is very greatly lessened. It follows that the life of the battery is very greatly increased, and under ordinary conditions it needs no attention for very long periods of time. It may also be observed that rotating the shaft in the wrong direction injures nothing, and that the apparatus is not likely to be disarranged by unskilled persons.

It is plain that my invention extends beyond the exact construction selected for illustration, and I do not therefore wish to limit my claims to those forms.

What I claim is:

1. In apparatus of the class described, the combination with a contact piece mounted to move in a predetermined path and to be moved from its normal position, during advance, by retarding or accelerating its movement, of a series of contact pieces fixed at intervals in said path, means for retarding and suddenly releasing the moving contact

piece as it approaches each fixed contact piece, and a spring yieldingly resisting both the retardation and the counter movement beyond normal position.

5 2. The combination with a series of fixed contact pieces, of a co-acting contact bar mounted to approach each of the fixed pieces in succession and pivoted to swing freely forward and rearward from its normal 10 alinement during such approach, means for retarding and suddenly releasing the bar as it approaches each fixed piece and a spring arranged to resist both retardation and the movement of the bar forward past its normal 15 position when released.

3. The combination with a series of contact pieces mounted in a circle, of a travelling contact piece mounted to move around the circle making contact with the fixed 20 pieces in succession and to be moved from its normal position, during advance, by retarding or accelerating its movement, spring devices permitting while resisting both retardation and the opposite movement beyond 25 normal position, and means for retarding and suddenly releasing the travelling contact piece as it approaches each of the other contact pieces.

4. The combination with a rotatable plate, of a contact bar pivoted freely between its ends upon the plate, a series of fixed contact pieces in the normal path of the outer end of the bar, means for retarding and then suddenly releasing the outer end of the bar as it approaches each fixed piece, and a spring yieldingly resisting the swinging of the bar in either direction upon its pivot. 30 35

5. The combination with a rotary shaft, of a centrally and freely pivoted laterally extending contact piece carried by the shaft, a series of contact pieces arranged in the path of the outer end of the pivoted contact piece, an alining spring connected to the opposite end of the pivoted piece and adapted to resist its swinging in either direction on its pivot, and means for retarding and suddenly releasing the outer end of the pivoted piece as it approaches each of the other pieces. 40 45

In testimony whereof I affix my signature in presence of two witnesses.
